United States Patent Office

Des. 229,615
Patented Dec. 18, 1973

229,615

COMBINED DATA ENTRY AND DISTRIBUTION TERMINAL

George E. Chadima, Jr., 3624 Skylark Lane SE,
Cedar Rapids, Iowa 52403

Filed Feb. 4, 1971, Ser. No. 112,838

Term of patent 14 years

Int. Cl. D14—02

U.S. Cl. D26—5 C

Fig. 1

Fig. 2

FIG. 3

FIG. 4

FIG. 1 is a perspective view of a combined data entry and distribution terminal showing my new design.

FIG. 2 is a left side view thereof, the right side being substantially a mirror image thereof;

FIG. 3 is a top view; and

FIG. 4 is a rear view thereof.

I claim:

The ornamental design for a combined data entry and distribution terminal, substantially as shown and described.
